UNITED STATES PATENT OFFICE.

CHARLES EDWARD HAY, OF ESSEX, ENGLAND.

TELEGRAPHY.

1,357,199.

Specification of Letters Patent. Patented Oct. 26, 1920.

Application filed November 14, 1916. Serial No. 131,235.

To all whom it may concern:

Be it known that I, CHARLES EDWARD HAY, a subject of the King of England, residing in Essex, England, have invented 5 certain new and useful Improvements in Telegraphy, of which the following is a specification.

This invention relates to systems of telegraphy of the kind in which a periodically 10 varying voltage is constantly impressed upon the signaling circuit, and is modified to constitute a signal.

The present invention is of a telegraphic system of the kind described, wherein the 15 means to energize the signaling circuit is such as to impress thereon a sine-wave or other smoothly changing periodic voltage and the arrangement is characterized by being such that the frequency of the voltage 20 is not changed by the act of signaling; in result a voltage curve is obtained having substantially uniform horizontal spacing for each whole period. The object of this arrangement is to avoid the disturbance of 25 the duplex balance which arises from a change in the frequency.

Provision is made according to this invention for effecting a signal by modifying the internal electromotive force of the generator 30 which supplies the signal impulses, or, alternatively, by modifying the position of the earthing point relatively to the extreme positive and negative points in the generator; again, alternatively, both these 35 methods may be employed in combination. The said modification of the position of the earthing point is conveniently effected by providing the generator with one or more tappings each of which may be connected 40 to earth or otherwise brought to zero potential at will.

In one embodiment of this invention an oscillatory electrical circuit, maintained in oscillation by impulses from a battery 45 through a synchronously driven reversing commutator is employed as the generator and means are provided to earth at will one of a number of selected points on the battery.

50 One method of carrying out this invention is illustrated in the accompanying drawings in which—

Figure 1 is a diagrammatic representation of the apparatus and electrical circuits;

Fig. 2 is a perspective view of a detail of 55 part of the apparatus of Fig. 1;

Fig. 3 is a diagram illustrating the kind of signal transmitted by the apparatus of Fig. 1;

Fig. 4 is a perspective diagrammatic view 60 of a preferred construction of a detail, and

Fig. 5 is a diagram, explanatory of an arrangement illustrating the fundamental principle of this invention, and

Figs. 6, 7 and 8 are diagrams of signals 65 sent by the arrangement of Fig. 5.

Referring first to Figs. 1, 2 and 3, the point of junction A of the telegraph cable A₁ and artificial line A₂, connected for duplex work is connected to a point between 70 an inductance B and a condenser C which are connected together to constitute an oscillatory circuit, which circuit is completed through an earth connection C₁, an earth connection C₂ and a commutator D, a battery being inserted in the manner herein- 75 after to be described between the commutator D and earth connection C₂.

The commutator D comprises two sections of the general shape indicated in perspective 80 at D₁ in Fig. 2, and is provided with three brushes, namely the brush E connected to the inductance B and the brushes E₁ and E₂ connected respectively to the tongues F₁ F₂ of relays G₁ G₂. The relays G₁ G₂ are 85 energized from a battery G and the tongues F₁ F₂ play between contacts to control the current from a battery subdivided into four portions H₁ J₁ H₂ J₂, all in series with one another, the center point H of which is connected to earth by the connection C₂. 90

A perforated tape K of the well-known kind co-operates with brushes, or, as they are commonly called, prickers, K₁ K₂ to complete the circuit of the battery G 95 through a metallic platform J over which the tape K travels in the direction of the arrow k.

The upper contacts of the relays G₁ G₂ are connected to the free ends of the batteries J₁ J₂ respectively, while the lower contacts of these relays, toward which the tongues are spring-impelled, are connected to the junction points of the battery J₁ with H₁ and the battery J₂ with H₂ respectively. 100 105

The commutator D is driven by means of a small motor D₂ which also serves to drive a sprocket-wheel D₃ engaging with the cen-

ter perforations of the tape K, the gearing D₄ between the motor and the wheel D₃ being such that the commutator makes one complete revolution during the time the tape takes to move a distance equal to that separating two successive holes of the center row of perforations.

On either side of the said center row, which row is exclusively employed for the purpose of shifting the tape, are other perforations, hereinafter referred to as the signaling perforations, the row which coöperates with the pricker K₁ being intended to transmit dashes and that which coöperates with the picker K₂ being intended to transmit dots.

The operation of the apparatus depicted in Fig. 1 is as follows. The inductance B and condenser C when closed upon themselves through the point A and the earthing connections C₁, C₂ constitute an oscillatory circuit which has a natural period of its own, but this natural period is modified by the cable A₁ and line A₂, together with their appurtenances, being connected to the circuit at the point A and also through the earth connection C₁. The oscillatory circuit with the connected parts therefore possesses a natural period of oscillation different from that which it would have if it consisted simply of the inductance B and condenser C.

The motor D₂ is speeded up to drive the commutator D so that it makes one complete revolution in precisely the time of the said modified period.

Under normal conditions, when the circuit is not being employed to send signals, the two tongues F₁, F₂ of the relays both rest upon their lower contacts.

Under these conditions the batteries H₁, H₂ are connected alternately to the oscillatory circuit through the brushes E₁, E₂ and the brush E, by the operation of the commutator. The batteries H₁, H₂ serve to maintain the oscillations in the circuit, including the inductance B and condenser C, with the result that a sinusoidal-wave of electro-motive force is impressed upon the sending circuit, as is indicated at L in Fig. 3.

When, however, the tape causes one of the prickers to make contact with the platform J one of the relays G₁, G₂ is operated. As illustrated in Fig. 1 the pricker K₂ is coöperating with one of the signaling perforations for a dot to close the circuit from the battery G through the relay G₂ and metallic platform J and the tongue F₂ of the latter is thus pulled against its upper contact. The battery J₂ in addition to the battery H₂ is thus put on to the brush E₂ and, as the commutator revolves to put the brushes E, E₂ into conducting connection, the battery J₂ also is applied to the oscillatory circuit and increases its negative amplitude, thus producing a signal such as is indicated

in the space L₁ of the record shown in Fig. 3. A series of signaling perforations coöperating with the pricker K₂ would give a series of repeated signals, similar to that in the interval L₁. On the other hand, a series of signaling perforations coöperating with the pricker K₁ would produce a series of signals such as those indicated at L₂ in Fig. 3, since the relay G₁ will now be operative to lift its tongue F₁, while the tongue F₂ will have fallen back upon its lower contact.

In the well-known manner the signal indicated at L₁ may represent a dot while each of those indicated at L₂ may represent a dash. The combination of L₁ and L₂ represents the letter A, while the second one at L₂ followed by three similar to that at L₁ represents the letter B and the remaining four signals of Fig. 3 represent the letter C in the customary manner.

It is to be understood that the relays G₁ and their tongues F₁, F₂ playing between fixed contacts are merely given in a diagrammatic sense to explain the operation. The butting contacts of oscillatory tongues playing between fixed points do not conduce to the best working, owing to the liability of the tongues to chatter upon the contacts. It is preferred to employ, instead of a tongue playing between two contacts, a commutator upon which there rest two brushes, and cause the relay to lift one or the other of the said two brushes instead of moving a tongue over from one contact to another. Such an arrangement is indicated diagrammatically in Fig. 4 as applied to the right-hand half of the apparatus of Fig. 1. The relay coil G₂ is there shown controlling the positions of two brushes M₁, M₂ to cause one or other of them, but only one, to rest upon a contact wheel M which is connected by a third brush M₃ to the brush E₂ of the commutator D. The brush M₁ is connected to the point of junction between the batteries H₂, J₂ and normally rests upon the wheel M, whereas the brush M₂ is connected to the free end of the battery J₂ and is substituted for the brush M₁ by the action of the relay G₂ when excited. The brushes M₁, M₂ are suitably insulated from one another and the operation of the armature G₂ of the relay so adjusted that only one of these two brushes at a time can make contact with the wheel M. Thus in the position shown the batteries H₂, J₂ in series with one another are in readiness to be applied to the oscillating circuit through the brush E₂ so soon as the commutator D enables this to occur.

As a result when a tape perforated as is the one shown in Fig. 1 passes through the apparatus the signals sent are those indicated in Fig. 3, the wave with a high crest at L₁ being due to the pricker K₂ being in contact with the platform J.

A feature which lies at the root of the

present invention is that by which the signaling is effected by the operation of varying at the sending end, the point in the oscillations which is at zero potential and therefore by varying the distribution of line potential at the receiving end. In order to render this clear an arrangement embodying the invention in a more simple manner than the arrangements of Figs. 1 to 4 is shown in the 10 diagram of Fig. 5.

In Fig. 5 a battery is connected by its middle point h to the upper contact of a relay g_1 by its positive end H' to the brush E_1 of the commutator D , and by its negative 15 end h_2 to the brush E_2 of the commutator D . These parts D E_1 and E_2 are as in Figs. 1 to 4, as are also the parts A , A_1 , A_2 , B , C , C_1 and E .

The terminal h_1 of the battery is connected 20 to the lower contact of the relay g_1 and the terminal h_2 to the lower contact of a relay g_2 . The tongue of the relay g_1 is connected to the upper contact of g_2 and the tongue of g_2 is connected to earth. Each of these 25 tongues is normally spring-pressed against its upper contact and the circuits of the relay windings are controlled by tape machines or in any desired manner.

When the parts are in the positions shown 30 in Fig. 5 the impulses being sent are as shown in Fig. 9 since the rotation of the commutator (which is effected as shown in Fig. 2) puts h_1 and h_2 alternately in connection with E and maintains an equal and symmetrical 35 distribution of potential above and below zero by the aid of the oscillator constituted by the parts B and C . If now the tongue of relay g_1 be drawn on to its lower contact the end h_1 of the battery is put to earth and 40 signals as at Fig. 7 are sent. If the tongue of g_2 is drawn down, however, instead of that of g_1 the signals sent are as at Fig. 8. If both tongues happen to be down together the result is the same as if that of g_2 alone 45 were down. It will thus be clearly seen that the signals are effected entirely by changing the zero potential point and thus changing the distribution of the potential. The signals of Fig. 6 are read as spaces, 50 those of Fig. 7 as dashes and those of Fig. 8 as dots.

A further advantage of the system according to this invention is that, when applied to printing telegraph systems, for example 55 to the Baudot printing telegraph, it overcomes the present difficulties arising from the sending and receiving end getting out of synchronism. With the present invention, when such a printing system has been synchronized it remains in synchronism and is 60 not thrown out by the signaling operations. The reason for this is that when the sending of signals is effected by the sudden application and removal of an electro-motive force 65 to and from the line so that the graph of the

sending impulses has the appearance of flat-topped rectangular waves, the tendency is for the impulses at the receiving end to merge into one another so that in practice as much as 20% of each revolution of the 70 Baudot distributor is taken up with the operation of synchronizing the sending and the receiving apparatus. On the other hand when the sending impulses are in the form of sine waves of potential, they are received 75 at the far end in the same form, with the result that each impulse serves to contribute its own share to the synchronization.

In either of the arrangements, namely that shown in Fig. 1, or that shown in Fig. 4, 80 the generator represented by a subdivided battery for energizing the oscillatory circuit may be replaced by any other sub-divided generator, or suitably subdivided source of electromotive force.

What I claim as my invention and desire 85 to secure by Letters Patent is:—

1. In a telegraph system the combination of an oscillatory electrical circuit operatively connected to a telegraph line so as to impress thereon a voltage derived from oscillations in the said circuit, a sub-divided battery and a commutator operated at such a speed as to connect the battery to the oscillatory circuit at intervals which synchronize with the natural period of that circuit and said line jointly when connected together, and means to select automatically the point on the battery which the commutator serves to connect to the oscillatory circuit.

2. In a telegraph system, a telegraph line, an oscillatory electrical circuit operatively connected to the telegraph line so as to impress thereon a voltage derived from oscillations in the oscillatory circuit, a generator provided with tappings to give a plurality of diverse voltages, a commutator connecting the generator with the compound circuit formed by the said oscillatory circuit and telegraph line, means to drive the commutator at such a speed that the generator is periodically connected to the said compound circuit synchronously with the natural period belonging to that circuit, and means to select at will which of the said tappings constitutes a second connection between the generator and the said compound circuit.

3. In a telegraph system, a telegraph line, an oscillatory electrical circuit operatively connected to the telegraph line so as to impress thereon a voltage derived from oscillations in the oscillatory circuit, a generator provided with tappings to give a plurality of diverse voltages, a commutator connecting the generator with the compound circuit formed by the said oscillatory circuit and telegraph line and constructed to connect the compound circuit with two different tappings from the generator alternately, means to drive the commutator at such a speed that 130

the generator is periodically connected to the said compound circuit synchronously with the natural period belonging to that circuit, and means to select at will which of the said 5 tappings constitutes a second connection between the generator and the said compound circuit.

* In testimony whereof I have signed my name to this specification in the presence of two subscribing witnesses.

CHARLES EDWARD HAY.
